UNITED STATES PATENT OFFICE.

SVEN AUGUST ESKILSON AND KARL AXEL BERNHARD HOLM, OF STOCKHOLM, SWEDEN, ASSIGNORS TO AMERICAN GASACUMULATOR COMPANY, OF ELIZABETH, NEW JERSEY, A CORPORATION OF NEW JERSEY.

PILOT BURNER.

Application filed January 10, 1927. Serial No. 160,052.

In cases where gas is supplied at intervals to a main burner it is necessary that a constantly ignited pilot burner shall be associated therewith in order that when gas does escape from the main burner it will be ignited.

It has been found in practice that pilot burners are liable to become extinguished, such extinguishment being due to one cause or another. For instance, one cause of extinguishment of the pilot flame may be the use of impure gas which results in the clogging of the burner; another cause of extinguishment may be due to the excessive supply of gas to the burner which may result in the deposition of soot to such an extent as to interrupt the flame; or the extinguishment may be due to an inadequate supply of gas in consequence of which the flame is not sufficiently strong to withstand the gusts of wind; and it may be also that in such case the gathering of insects about the pilot burner might extinguish the same or a water spray or drops of water which might contact with the flame of the burner might effect its extinguishment.

The general object of the present invention is to provide a novel construction of pilot burner of such character that the flame thereof is not liable to become extinguished on account of any of the causes hereinbefore referred to, nor on account of any other happening to which the flame of such burner may be subjected.

It is also an object of the invention to provide a pilot burner of novel construction embodying means the presence of which protects the flame against strong gusts of wind.

Another object of the invention is to provide a pilot burner of novel construction of a character such that the flame produced thereby is of a magnitude sufficient to prevent its extinguishment due to the falling of water thereon or the gathering of insects thereabout and thereon.

A still further object of the invention is to associate with the main burner a plurality of pilot burners in operative relation thereto and to each other so that if the flame of one of said burners should become extinguished it may be relighted directly from the other of said burners, or the said other burner may effect ignition of the gas which may escape from the main burner, the flame of the lat-

ter effecting ignition of gas from the previously extinguished burner.

Another object of the invention is to provide a pilot burner of novel construction having means whereby the atmosphere may be, and is, caused to intermingle with the gas in the burner whereby complete combustion to effect the production of a blue flame is brought about.

To these and other ends the invention comprehends the construction of and arrangement of parts as hereinafter illustrated in the drawing, described in detail, and particularly pointed out in the claims. However, it will be understood that the invention may be embodied in other forms of construction than that shown and that changes in the details of the construction may be made within the scope of the claims without departing from the said invention.

In the drawing,

Fig. 1 is a view in central vertical section of the base or supporting structure for a main burner of well known type with which is associated the pilot burners embodying the invention, the said main burner, pilot burners and the pipes for conveying gas to the latter being shown in elevation;

Fig. 2 is a similar view taken in a plane at right angles to that in which Fig. 1 is taken;

Fig. 3 is a top plan view of the burner structure shown in Figs. 1 and 2;

Fig. 4 is a view taken on the line 4—4 of Fig. 2, the base portion of the structure being omitted and the pilot burners being shown in elevation;

Fig. 5 is a view showing the main burner partly in elevation, a portion thereof being broken away and shown in section to indicate a gas outlet, and one of the pilot burners being shown in vertical section and a portion of the other of said burners being shown in elevation; and

Fig. 6 is a view in perspective of one of the pilot burners separate from the other parts of the construction.

In the drawings we have shown a block 1 upon which is the main burner 2 detachably supported in known manner. The said burner may consist of any suitable material such as soap stone. This burner is of well known type terminating at its upper end in two branch portions 3 and 4 which

are provided upon their inner sides near their upper ends with gas outlet openings 5. The block or body member 1 is provided with a passageway 7 which leads to the lower end of the burner 2 through which gas is supplied to the gas outlets 5. The gas to the pilot burners, which will be hereinafter described, is supplied through a passageway 10, to a cross-wise extending passageway 11 which terminates at its opposite ends in enlarged portions 12 the outer end portions of which are screw threaded for the reception of plugs 13, which in turn are provided with axial screw threaded openings 14 with which are engaged adjusting screws 15 terminating at their inner ends in cone shaped pointed portions 16. The ends of the pointed portions 16 contact with washers 20 which are seated against the outer ends of porous bodies 21 of any preferred known construction, as for instance asbestos fiber the resilience of which is increased by means of the coiled springs 22 imbedded therein. By adjustment of the screws 15 the compactness of the fibrous bodies 21 may be varied so as to regulate and control the flow of gas from the cross-wise passageway 11 through the inner portions of the opening 12 and thence through the lower ends of the pipes 25, upon the upper ends of which are mounted the pilot burners of a design embodying our invention. These burners consist of box-like members 30 and 31, the former being directly associated with the branch 3 of the main burner while the latter is associated directly with the branch 4 thereof. The upper ends of these burners are open and shaped as shown and the sides thereof adjacent the branches 3 and 4 are provided with notches 32. The greater portions of the widths of these notches open upon or against the inner sides of the branches 3 and 4 with which they are associated. In order, however, that opportunity may be afforded for the thorough intermingling of air with the gas within the pilot burners there is between the inner edge of each notch and the adjoining side of the branch of the main burner with which it may be associated a slot or passageway 34. The relation of these slots or passageways to the adjacent sides of adjoining branches of the main burner is clearly shown in Figs. 1 and 3 of the drawing. The burners 30 and 31 are mounted in contact with each other as shown as that if the flame of one of them should become extinguished it (the said burner) is maintained in heated condition by reason of heat conducted thereto from the other burner, the burning of which continues. As a result of this relationship it is more than likely that the gas escaping from the burner of which the flame has been extinguished will be reignited from the other burner. But even if it is not so reignited

its ignition will be effected upon a resumption of a flow of gas from the openings 5 of the main burner which will be ignited by the flame of the burner which has not been extinguished. Preferably the contacting sides of said burners should be joined together by soldering, brazing or otherwise.

It will be apparent from an inspection of the drawing that the flames of the respective pilots are protected from drafts or gusts of wind except in cases where such drafts reach the burner by movement in a generally downward direction. If, for instance, there should be a current of air moving in a direction at right angles to the plane in which Fig. 2 is taken, it will strike the sides of the burners; if the air should be moving in a direction at right angles to that last supposed, one of the pilot burners will in large part be protected by the presence of one of the branches 3 or 4, while the other of said burners will be protected by the side thereof which faces toward the direction from which the wind may be coming. From whatever direction the wind may approach the burners, except in a downward direction, the pilot burner flames are well protected so that the liability of extinguishment thereof as a result of drafts or gusts of air is very greatly reduced.

As already indicated the presence of notches enables the intermingling of air with the gas within the interiors of the burners so that oxygen sufficient for complete combustion is supplied whereby blue flames result. When this is the case the deposition of soot which might close the burner passageway is prevented. Furthermore the burners are of a size to prevent clogging thereof due to soot or to impurities which may be present in the gas. Furthermore the pilot burners being of a character to produce a flame of large area or magnitude, such flame is able to resist more effectively drafts or gusts of air and also is not likely to be extinguished by the falling of water spray or rain thereon or by the presence of insects therearound or thereupon.

Having thus described our invention what we claim and desire to secure by Letters Patent is,

1. A pilot burner comprising a casing to which gas is supplied, the upper end of which casing is open and one side of which is provided with a notch, which notch opens out toward the body of the main burner with which the said pilot burner may be associated.

2. A pilot burner which is adapted to be associated with a main burner which pilot burner consists of a hollow casing having an open upper end, one side of said casing having a notch therein which notch opens toward the main burner with which the said pilot burner is associated, the said notch

being partially closed by the said burner and the said burner co-operating with an edge of the said notch to form a slot for the passage of air into the interior of the said casing, substantially as described.

3. In combination, a main burner consisting of two branches and a plurality of pilot burners supported between the said two branches, each of said pilot burners being 10 provided with notches in its side adjoining one of the said branches, substantially as described.

4. In combination, a main burner comprising branches angularly related to each 15 other, pilot burners mounted between said branches, each of said burners consisting of a hollow casing having an open upper end and also having an opening in a side thereof, which open upper end and side opening 20 are located near the outlet for the gas from the branch of the said main burner with which the said pilot burner may be associated, and means for regulating the supply of gas to the said pilot burners.

25 5. In combination, a main burner having two branches arranged in angular relation to each other, which branches are provided with gas outlet openings upon their inner

sides near their outer ends, a plurality of pilot burners supported in adjoining relation to each other between the said branches, the said burners consisting of box-like members open at their upper ends, one side of each of which is provided with a notch, each of said pilot burners being supported with 30 one of its sides in contiguous relation to the inner side of one of said branches, the said side of each pilot burner being provided with a notch, one edge of which forms a slot with the adjoining side of the associated 35 branch of the main burner, substantially as described.

6. In a structure of the character described, the combination of a main burner and a pilot burner associated therewith, one 40 side of said pilot burner being located in contiguous relation to the adjoining side of said main burner and having an opening therein which extends beyond one edge of 45 said side.

In testimony that we claim the foregoing as our invention we have hereunto signed our names this 22nd day of December, A. D. 1926.

SVEN AUGUST ESKILSON.
KARL AXEL BERNHARD HOLM.
